UNITED STATES PATENT OFFICE.

HUBERT PERCY BARRY, OF WAIHI, NEW ZEALAND.

HONEYCOMB LINING FOR TUBE-MILLS AND SIMILAR GRINDING AND CRUSHING MACHINES.

No. 887,575.

Specification of Letters Patent.

Patented May 12, 1903.

Application filed April 24, 1903. Serial No. 313,512.

To all whom it may concern:

Be it known that I, HUBERT PERCY BARRY, a subject of His Majesty the King of the United Kingdom of Great Britain and Ireland, resident of Waihi, in the Provincial District of Auckland and Colony of New Zealand, engineer, have invented Honeycomb Linings for Tube-Mills and Similar Grinding and Crushing Machines, of which the following is

10 a specification.

The purpose of this invention is to provide a cheap and effective grinding surface within tube mills and other grinding machines. This purpose is attained by fitting within the 15 tube mills, or grinding machines shallow frames or boxes of hexagonal or rectangular form shaped as is hereafter stated and fixing therein a material composed of rough blocks of stone or other substances suitable for the 20 purpose as hereunder described.

The accompanying drawing shows sixteen figures of which

Figure 1 is a plan illustrating a portion of the inside of a tube mill and showing different formations of frames or segments with material fixed in parts, Fig. 2 is a cross section through $z-z$ of Fig. 1, Fig. 3 is a plan of a formation of frame or segment, Fig. 4 is an end elevation of the frame or segment shown in Fig. 3, Fig. 5 is a section through $w-w$ of Fig. 3, Fig. 6 is a plan of a formation of a frame box or segment showing its sides grooved and locking bar, Fig. 7 is a side elevation of Fig. 6, Fig. 8 is an end elevation of Fig. 6, Fig. 9 is a section through $y-y$ of Fig. 6, Fig. 10 is a plan of another formation of a frame box or segment showing its sides rabbeted for interlocking, Fig. 11 is an end elevation of Fig. 10, Fig. 12 is a section through $z-z$ of Fig. 10, Fig. 13 is a plan of a plain sided formation of a frame box or segment, Fig. 14 is a side elevation of Fig. 13, Fig. 15 is an end elevation of Fig. 13, and Fig. 16 is a section through $v-v$ of Fig. 13.

45 The tube shell A of the grinding mill is shown in Figs. 1 and 2 in part and broken as it is only necessary to show a portion to illustrate the different formations or segments B fixed and which may be fixed therein, Fig. 2 being a cross section only the depths of the 50 formations or segments B are shown, but Fig. 1 being a plan their shapes are shown more fully so that the idea of their purpose can be fully seen while the rough stones C shown in

both Figs. 1 and 2 quite illustrate the advantage of their use.

The frame and box formations B hereinafter called segments are made with or without bottoms of iron steel or other suitable material and in convenient sizes shaped to fit inside the tube mill as shown in Figs. 1 and 2 and to retain the lining material in position. The segments B may have ribs or bars D preferably shaped across to help hold the lining material C in place and so as to limit and 60 reduce the size of the segments B into smaller compartments E to suit the particular nature of the lining material used, or rib or bar formations D may be used by themselves without outer frames as shown in Fig. 3.

The outsides F of the segments B may be formed plain and made to the radius of the tube mill and so form an arch which will key each segment B in position or the outsides G of the segments B may be rabbet formed so 65 as to interlock with grooves therein into which locking bars J of iron or steel or other suitable material may be put. The segments B may be bolted or otherwise suitably 70 connected to the tube mill but as a rule this will be unnecessary.

To prepare the segments B for use they are placed upon a firm surface approximately of the same radius as the inside of the tube mill when they the segments B are well filled 75 with the lining material either in the form of concrete K or of rough blocks of stones C, the stones being jammed in tightly and the interstices between them being filled and rammed with cement concrete or cement 80 mortar M or suitable material which can be poured in in the shape of grouting if the spaces between the stones are small. The lining material may be fixed to be quite rough as shown at C in Fig. 2 and it will preferably be made to project in irregular formations above the edges of the segments B and ribs or bars D as it will thereby protect the edges from undue wear and by its irregular surface assist the grinding capacity of 85 the tube mill or machine. The lining material may be of quartz or any hard rock or material that will do the work required of it.

After giving the cement concrete or cement mortar M of concrete K or other lining 90 material in the segments B ample time to set hard the segments B are built into the tube mill or machine with cement or other

suitable binding material and the locking bars J are driven in when found necessary to use them. If found advantageous to do so the segments B may be built into the tube mill or machine empty in the first place and then the different compartments can be filled with the lining material in the manner above described.

When the different segments B have been fitted within the tube mill or machine and the lining material filled and fixed therein the tube mill or machine will be worked in the usual way but with a much more effective and marked result than is now obtained without the use of the lining material herein specified.

After the tube mill or machine has been working for some time the lining material should be examined and if any of it is found to be faulty or unfit for use the segment B into which it is fitted or fixed can be refitted by having the faulty lining chipped, broken, and taken out and fresh lining material filled in in the manner already described.

Figs. 3, 6, 10 and 13 illustrate the different formations of segments B which may be used to hold the lining material in position, these formations are also shown in Figs. 1 and 2 and another formation N is shown in these two figures which is clear of ribs or bars so that concrete K can be bodily filled therein as is shown in Figs. 1 and 2.

Having fully described my invention what I desire to claim and secure by Letters Patent is:

1. As an article of manufacture, a grinding mill segment having an opening, a plurality of crushed stones set in said opening, and cement for permanently holding the stones in the opening, the exteriors of the stones being left in a rough condition and extending beyond the outer surface of the segment to constitute a grinding area.

2. The combination of a plurality of grinding mill segments set side by side and having grooves in their sides, keys fitted in the grooves to interlock the segments together, the segments having openings, a plurality of stones set in the respective openings, and cement material to hold said stones permanently in place in the said openings, the exteriors of the stones being roughened.

3. The combination of a plurality of grinding mill segments set side by side, means for uniting said segments to present a shell, the segments having openings, a plurality of stones set in the respective openings, and cement material to hold the stones permanently in place in the said openings, the exteriors of the stones being roughened.

HUBERT PERCY BARRY.
